UNITED STATES PATENT OFFICE.

LESTER F. BEAULIEU, OF LINCOLN, CALIFORNIA, ASSIGNOR OF ONE-HALF TO
CORNELIUS R. KENNEDY, OF LINCOLN, CALIFORNIA.

VACUUM CLEANING ATTACHMENT FOR MOTOR VEHICLES.

Application filed October 5, 1926. Serial No. 139,599.

This invention relates to improvements in vacuum cleaning devices, and particularly to one for motor vehicles; my principal object being to provide a suction fan arranged to be driven by the exhaust gases of the vehicle, and a suction line permanently extending from the fan to a convenient point on the vehicle, so that a vacuum cleaning nozzle of any suitable character can be attached to 10 the suction line and operated inside the vehicle.

A further object is to provide a device for the purpose constructed as an attachment, which may be readily interposed in and 15 permanently connected to the exhaust pipe of any motor vehicle in a position most convenient.

My device should, I believe, fill a long-felt want, especially in connection with cloth-upholstered closed cars, which of course collect dust and dirt which it is almost impossible to eliminate with ordinary means. Vacuum 20 cleaning devices being recognized as very efficient, some car owners have attempted to utilize their house vacuum cleaning attachment in their cars. Such equipment, however, is not intended for this purpose and is 25 awkward and hard to manipulate in the cramped quarters, besides necessitating leading a hose or the like from outside the car into the same, increasing the inconvenience 30 of operation. My device on the other hand is self-contained within the vehicle.

A further object of the invention is to 35 produce a simple and inexpensive device and yet one which will be exceedingly effective for the purpose for which it is designed.

These objects I accomplish by means of such structure and relative arrangement of 40 parts as will fully appear by a perusal of the following specification and claims.

In the drawings similar characters of reference indicate corresponding parts in the several views:

45 Fig. 1 is a fragmentary side section of a motor vehicle showing the mounting of my vacuum cleaning attachment thereon.

Fig. 2 is a sectional elevation of the exhaust pipe coupling sleeve and driving member associated therewith.

50 Fig. 3 is a transverse section of the vacuum creating attachment, taken on the line 3-3 of Fig. 2.

Fig. 4 is a side elevation of the attach-

ment with the cover on the suction fan 55 chamber removed to show the fan.

Referring now more particularly to the characters of reference on the drawings, the numeral 1 denotes a sleeve of suitable length and of a diameter such as to enable it to fit snugly at both ends of the exhaust pipe 2 of the engine 3 of the vehicle; said pipe being cut and a short length removed when mounting the sleeve thereon. The sleeve may be rigidly held onto the pipe by any suitable 60 means, such as set screws 4 tapped into the sleeve.

Projecting from the sleeve intermediate its ends is a passage 5 which leads to a cylindrical chamber 6 in which a multivaned turbine wheel 7 is mounted. A portion of the periphery of the chamber opposite to the passage 5 is cut away so as to permit escape of the gases after they have acted on the turbine. Turnably mounted in the sleeve at 70 the junction of the rear end of the passage 5 with the sleeve is a flap valve 8, adapted to be moved to close the sleeve beyond the passage, so that the gases from the engine must enter said passage to rotate the wheel; or to be moved to close the passage so that 75 the gases will travel directly through the sleeve and to the outer end of the exhaust pipe without affecting the turbine. The stem 9 of this valve has a handle 10 of 80 suitable form on its outer end so the valve may be manipulated at will.

The shaft 11 of the wheel is journaled in one wall of the chamber 6 and projects therethrough into another chamber 12 which is 85 disposed immediately adjacent the chamber 6 and is preferably formed as a unitary part of the sleeve 1 and said chamber 6. Fixed on the shaft 11 and turning in the chamber 12 is a centrifugal suction fan 13 of suitable 90 form. The outlet passage 14 from the fan chamber preferably projects rearwardly, while the intake passage 15 which is centrally aligned with the shaft 11, as is customary, is adapted for connection to a length of hose 100 or pipe 16. This hose preferably extends upwardly and adjacent the forward side of the engine bulkhead 17 of the vehicle, being connected at its upper end to a suitable form of quick connection coupling 18 which is permanently attached to the rear side of the bulkhead in a location convenient to be reached by the operator. The coupling may 105

however be located in any other position desired.

It will thus be seen that when the exhaust gases from the engine are permitted to enter the passage 5, the turbine will be driven, which in turn will cause the suction fan to be driven. This sets up a suctional force through the hose 16 toward the fan, as will be evident.

10 The above described parts are permanently installed on the vehicle. A suction nozzle 19 of any standard and suitable type, and having a length of flexible hose 20 sufficient to enable the nozzle to be used throughout 15 the interior area of the car, is provided with these permanent parts for detachable connection to the coupling 18.

From the foregoing description it will be readily seen that I have produced such a device as substantially fulfills the objects of 20 the invention, as set forth herein.

While this specification sets forth in detail the present and preferred construction

of the device, still in practice such deviations from such detail may be resorted to as do not 25 form a departure from the spirit of the invention, as defined by the appended claims.

Having thus described my invention what I claim as new and useful and desire to secure by Letters Patent is:

Operating means for a vacuum cleaning attachment comprising a turbine wheel, a suction fan mounted in driving relationship with said wheel, a passage member leading to the wheel, and a sleeve tapped intermediate its ends by said member, and having valve means to permit of a direct flow through the sleeve from one end to the other and selectively from one end into the passage; the ends of the sleeve being in common longitudinal alinement and being arranged to fit the separated ends of a gas-engine exhaust pipe.

In testimony whereof I affix my signature.

LESTER F. BEAULIEU.
